HONING DEVICE FOR CYLINDERS
 Paul R. Gjertsen, 3513 Dearborn Ave., Detroit 17, Mich.
 Filed Dec. 2, 1960, Ser. No. 73,397
 1 Claim. (Cl. 51—184.2)

This invention relates to a honing device for cylinders and the like, and more particularly to a novel mounting mechanism for the cylinder engaging elements thereof.

Heretofore, in certain types of honing devices, there are employed a plurality of radially extending right angularly related cylinder engaging elements normally of an abrasive character, some of which may be non-abrasive, and resilient for cooperative stabilizing engagement with the interior of the work surface, and wherein cylinder engaging element included a pair of radial bars slidably provisioned within a central rotative carrier, with the said bars having secured at their outer ends as a part thereof, a cylinder engaging element.

The difficulty was that with the wear of the abrasive element, or the resilient element of the cylinder engaging member, it was necessary to replace the complete cylinder engaging element, including the said shafts and supporting channel.

It is therefore an object of the present invention to provide a novel form of cylinder engaging element wherein in a channel assembly is provided for holding either an abrasive element, or a resilient element for operative engagement with the interior of a work surface to be honed, and wherein the said channel element is removably mounted upon the axially adjustable supports and is easily replaceable, without replacement of the said supports.

It is a further object of the present invention to provide upon the radially adjustable support members, a clip mechanism whereby the abrasive or resilient elements may be removably mounted and fixedly secured in position, as desired.

These and other objects will be seen from the following specification and claim in conjunction with the appended drawing, in which:

FIG. 1 is a fragmentary side elevational view of a honing device incorporating the present invention.

FIG. 2 is a fragmentary plan view thereof taken on line 2—2 of FIG. 1.

FIG. 3 is a side elevational view of an abrasive cylinder engaging element as mounted upon its supporting channel member.

FIG. 4 is an end elevational view thereof.

FIG. 5 is a side elevational view of the leaf spring employed in the assembly of the abrasive mounting upon the fixed portion of the cylinder engaging element.

FIG. 6 is an end elevational view thereof.

FIG. 7 is a side elevational view of the base portion of the cylinder engaging element which is axially adjustable upon the carrier of the honing tool.

FIG. 8 is a fragmentary section taken on line 8—8 of FIG. 7.

FIG. 9 is a fragmentary side elevational view of the assembled cylinder engaging element with the abrasive holder interlockingly clipped with the mounting device.

FIG. 10 is a fragmentary section taken on line 10—10 of FIG. 9.

It will be understood that the above drawing illustrates merely a preferred embodiment of the invention and that other embodiments are contemplated within the scope of the claims hereinafter set forth.

Referring to the drawing, the present honing device for cylinders, includes an elongated carrier, generally indicated at 10 with longitudinally spaced enlargements 11 at its opposite ends with elongated shank 12, therebetween, having a longitudinal bore 13.

2

As shown in FIG. 1, a pair of longitudinally spaced transverse bores 14 are formed through end portions 11 of said carrier. An additional pair of longitudinally spaced bores are also formed through said carrier at right angles to the bores 14 with the said bores 14 intersecting the longitudinal bore 13 which extends through carrier 10.

The elongated pinion 15 extends loosely through bore 13 in the said carrier and is adapted for cooperative meshing engagement with the racks 18 formed on their respective opposite sides of the support shafts 16, which form a part of the respective plurality of right angularly related cylinder engaging elements generally indicated at 17.

15 In the present preferred embodiment of the invention there are four of said cylinder engaging elements arranged radially of the carrier 10 and at right angles to each other. For this purpose and in addition to the above described bores 14, additional longitudinally spaced bores are formed transversely through the respective ends of the carrier 10 displaced from each other so as to cooperatively receive the respective support shafts 16 of the individual cylinder engaging elements.

For example, the bores in the carrier which receive 25 the shafts of the left hand cylinder engaging element 17 are arranged so as to pass upon one side of the bore 13, whereas the opposite pair of bores adapted to receive the shafts 16 of the right hand cylinder engaging element 17 will pass upon the opposite side of the bore 13 to provide the necessary clearance upon rotary adjustment of the pinion 15 and corresponding radial adjustments of the respective cylinder engaging elements, as hereinafter described.

The drive ring 19 concentrically receives one end of carrier 10 and is pivotally connected thereto upon its opposite diametrically opposed sides by the fasteners 20. The bifurcated stirrup 21 is right angularly related with respect to the pivotal connections 20 with its free ends bearing against diametrically opposite sides of the ring 19 and connected thereto by the fasteners 22.

40 The said stirrup 21 terminates in the shank 23 adapted to receive and have secured thereto a conventional power driven spindle 24 fixedly secured as by the lock nut 24' with respect to the said stirrup and shank, being 45 a means of transmitting rotative motion to the carrier 10. Though not necessarily forming a part of the present invention manual control means are provided for adjusting the radial positioning of the cylinder engaging elements 17, depending upon the size of the bore of the cylinder to be honed.

The adjusting means consists of a gearing assembly 25 interconnected with the pinion 15 so that rotation of the said assembly 25 affects rotary movement of the said pinion with respect to carrier 10 and consequent radial 55 adjustments of the cylinder engaging elements 17 simultaneously. A knurled adjusting member 26 is secured to the adjusting means 25, being in threaded engagement with the extension 27, which projects axially from the carrier 10 and which has a spring bias applied thereto 60 by the coiled spring 29 adjustably mounted on the extension 27 by the nut 28 for regulating the tension therein.

Accordingly on rotation of the adjusting means 26 and the pinion 15, it is seen that in view of the gear connection between the said pinion and the racks 18, each 65 of the cylinder engaging elements 17 may be adjusted radially inwardly or outwardly with respect to carrier 10, with the said elements moving in unison and with their outer cylinder engaging surfaces all at the same 70 radius.

The present invention is particularly directed to the

structure of the cylinder engaging elements 17, now described in further detail with respect to FIGS. 3 through 10, and includes an elongated bracket support having an elongated rectangularly shaped base 30 from which projects the pair of parallel spaced support shafts 16, which carry upon their one sides the racks 18, as above described.

Top plate 31 is fixedly secured over the base plate 30 and at its ends corresponding to the respective ends of said base plate has a pair of opposed inwardly directed channels 32—33, best illustrated in FIG. 7, and defining therein the receiving slots 34 at the opposite ends of the top plate 31. Also a pair of longitudinally spaced notches 35 are formed within the top plate 31 adjacent one edge thereof adapted to cooperatively receive the stops 42 of similar shape when the removable channel 36 is mounted thereon as hereinafter described.

In the preferred embodiment of the invention, there are four cylinder engaging elements 17, one opposed pair, such as the pair shown in FIG. 1 carrying an abrasive stone 39 of a suitable abrasive material such as Carbide. The diametrically opposed right angularly related additional cylinder engaging elements normally do not carry abrasive elements, but on the other hand, carry a suitable resilient longitudinally extending cylinder bore engaging strip 45, which is non-abrasive, but which is resistant to wear and may be constructed of rubber or neoprene, or any suitable felt or fabric or mohair, or metal such as diecast material.

The primary purpose of the additional oppositely arranged resilient cylinder engaging elements 45 is to establish a degree of stability of the honing tool with respect to the bore of the work being honed for the purpose of minimizing and preventing vibration and for properly centering the honing tool. Each of the cylinder engaging elements 17 includes, however, an elongated channel 36, as shown in FIGS. 3, 4 and 9, two of which will have fixedly cemented or otherwise secured thereto as at 37, the elongated and longitudinally extending abrasive stones 39, being arranged upon the outer surface of the respective channels.

In the preferred embodiment, illustrated in FIG. 4, the said abrasive stones 39 abut the longitudinal flange 38 which defines a locating and retaining means for the said stone 39, being arranged upon the side of the stone in opposition to the direction of rotation of the tool and for the taking up of some of the thrust applied to the said stone on rotation of the honing tool.

The respective elongated channel 36 is adapted for superimposition upon the bracket support 30—31—32—33. Suitable clip means are incorporated upon undersurface portions of channel 36 adapted for interlockingly retaining engagement with the bracket support, and particularly the channels 32—33—34 formed at its opposite ends.

The abrasive stone 39 is arranged upon the outer surface of the channel, as shown in FIGS. 3 and 4. The aforesaid clip means are arranged upon the inner or upon the opposite surface of the channel 36 at its opposite ends and are defined by the outwardly extending transverse flanges 41 with the included transverse slots 40 thereover.

In normal use, the channel assembly 36 is placed in lateral registry with one side of the bracket support 30—31, adjacent the notches 35 so that the outwardly projecting flanges 41 are in registry with the grooves 34 defined by the end channels 32—33. At the same time, the above described transverse grooves 40 cooperatively receive the inwardly directed flanges 33, which form a part of the above described end channels 32—33—34. The said channel 36 is then projected laterally inward and over the bracket plates 30—31 so as to be superimposed thereon with the inward position of the channel

determined by registry of the stops 42 within the longitudinally spaced notches 35 upon one side of the top plate 31.

An undercut elongated notch 43 is formed in the undersurface of channel 36 in order to nest and retain therein the elongated formed leaf spring 44 which is interposed in compression between the said channel and the bracket support 30—31, for the purpose of frictionally retaining the interlocked relationship between the said channel and the said bracket support, and to serve as an automatic feed to compensate for wear of the abrasive element.

The assembly is such, and the notches 35 so arranged that in operation the tendency of the channel 36 is to be retained within and upon a bracket support 30—31, with the said stops 42 snugly nested within the notches 35 completing the assembly.

Accordingly, from time to time, as the abrasive stones 39 wear and need replacement, it is merely necessary to disengage the channel 36 from the bracket support by manual outward sliding movement by which a new channel may be introduced. By this construction, it is no longer necessary to discard the complete cylinder engaging element generally indicated at 17, as heretofore has been the case. All that is necessary now is to remove the one stone with associated channel 36 and replace it with another of the same type.

The construction of the showing oppositely arranged pair of cylinder engaging elements 17 in FIG. 1, is exactly the same. As to the right angularly related cylinder engaging elements 17, one of which is shown in FIG. 1, these also include elongated channels 36 of the same construction, as above described. However, instead of mounting and having secured thereon the abrasive stones 39 there is mounted and secured upon the said channel 36 by cementing preferably a resilient fibrous cylinder engaging element of a non-abrasive character, as above mentioned. As these wear, these may also be replaced in the same manner, as above described.

Having described my invention, reference should now be had to the following claim.

I claim:

In a honing device for cylinders, a power rotated carrier, a cylinder engaging element on said carrier, including an elongated bracket support parallel to the axis of rotation of said carrier, a pair of spaced shafts secured at their one ends to said bracket support and at their opposite ends adjustably mounted upon and through, and radially adjustable outwardly of said carrier, an elongated channel mounted on said bracket support, an elongated cylinder engaging abrasive stone secured to and upon the outer surface of said elongated channel, and clip means on the inner surface of said elongated channel, removably interlocked with said bracket support, said bracket support including an elongated base plate, opposed inwardly directed channel flanges upon the opposite ends of said base plate, said clip means including transverse projections at opposite ends of said elongated channel, nested with said base plate channel flanges, and spring means interposed in compression between said elongated channel and bracket support, there being a pair of longitudinally spaced notches formed in said base plate on one side thereof, and a pair of longitudinally spaced keys depending from said elongated channel retainingly nested within said notches.
